EXTENSION LADDER

Stanley E. Dunn, Montgomery, Pa.

Application August 25, 1938, Serial No. 226,785

6 Claims. (Cl. 228—66)

This invention relates to an improved attachment for releasably retaining a section of an extension ladder in an elevated position.

It is an aim of this invention to provide an apparatus for use with extension ladders adapted to be automatically actuated when released for retaining a section of the ladder in an elevated position and provided with means connected thereto for raising and lowering said section, said 10 means being adapted to retract the ladder holding member and to hold it retracted while said section is being raised and lowered.

It is an important object of the invention to provide an apparatus of the aforementioned type 15 which will be automatically actuated to lock the ladder section should the hoisting rope be accidentally released or break.

Still a further object of the invention is to provide a connecting member for sections of an extension ladder having a plurality of spaced integrally formed hooks each of which is adapted to cooperate in releasably engaging one of a plurality of ladder rungs for supporting one of said sections relatively to the other, and means connected to one of said hooks for normally retaining the hooks in a projected position.

Other objects and advantages of the invention will hereinafter become more fully apparent from the following description of the drawing, which 20 illustrates a preferred embodiment thereof, and wherein:

Figure 1 is a front elevational view showing the invention attached to an extension ladder,

Figures 2, 3 and 4 are vertical sectional views 25 taken on the lines 2—2, 3—3 and 4—4, respectively, of Figure 1, and

Figure 5 is a horizontal sectional view taken on the line 5—5 of Figure 1.

Referring more particularly to the drawing, 30 wherein like reference characters designate like or corresponding parts throughout the different views, 10 designates generally an extension ladder comprising the sections 11 and 12 which are held together by means of the members 13 which 35 are secured at their corresponding ends to the side rails of the section 11 and which are provided with the outwardly offset free ends 14 adapted to loosely engage the side rails of the section 12, and the members 13' which are secured 40 at their corresponding ends to the side rails of section 12 with their free ends 14' bent to engage around the side rails of section 11 to cooperate with the members 13.

A connecting member 15, as best seen in Figure 1, comprises the two corresponding hooks

16 the shanks of which are rolled at 17 to loosely engage the bottom rung 18 of the section 12 to pivotally mount the member 15 thereon. The shanks of the hooks 16 adjacent their hooked ends 19 are connected by a bar 20. A hook 21 is formed integral with the bar 20, intermediate of its ends, and is provided with a hooked end 22 at its upper end, formed by bending the shank of the hook 21 back upon itself and then outwardly, as best seen in Figure 4, to form the eyelet 23 therein. Hook 22 is in alignment with the hooks 19, for a purpose which will hereinafter be explained. The opposite end of the shank 21, which depends below the bar 20 is bent to form a hook 24 which projects in the opposite 15 direction to the hook 22.

A spring 25 has its opposite ends 26 secured to the rung 18 and then coiled several times around the rung with its intermediate portion 27 extending upwardly to engage the hook 24 to urge the 20 member 15 forwardly and downwardly or toward the rungs 28 of the ladder section 11. It will thus be seen that the hooks 19 and 22 will be normally urged into a position for engagement 25 with one of the rungs 28.

One end of a hoisting cable 29 is secured to the eyelet 23, said cable extending upwardly therefrom and being trained over a pulley 30, which is secured to and depends from the upper rung 28 of the ladder section 11. Cable 29 then extends downwardly along the underside of the ladder section 11, around its lower rung 28 and then upwardly with its opposite end secured to the rung 18.

The operation of the extension ladder is as 35 follows: by pulling downwardly on the portion of the cable 29 which extends along the underside of the ladder, member 15 will be swung upwardly and backwardly to a retracted position, against the action of the spring 25, with its hooks 19 and 22 out of engagement with the rungs 28 and may be so held by the weight of the ladder section 12 so that section 12 may be hoisted by pulling downwardly on the intermediate portion 40 of cable 29 or may be lowered by gradually paying out the intermediate portion of the cable. When it is desired to connect the hooks 19 and 22 to a particular rung 28 the ladder section 12 is hoisted by the cable 29 until the hooks 19 50 and 22 are slightly above the rung 28 and the cable 29 is then released suddenly so that the spring 25 will immediately project the member 15 before the section 12 has a chance to drop so that when it begins to drop the hooks 19 and 55

22 will engage the desired rung 28 to retain the section 12 in the desired elevated position.

The ladder 10 if used at locations where the structures against which the ladder is to be leaned have overhanging portions which the section 12 is to be hoisted past, the ladder 10 is inverted, from the position as seen in Figure 1, so that the section 12 is on the underside and so that the intermediate portion of the cable 29 is 10 facing the operator who in hoisting the cable 29 to raise the section 12 may pull outwardly thereon to draw the ladder 10, as a unit, from a diagonal position to substantially a vertical position so that the section 12 will move past the 15 aforementioned overhanging projection.

Various modifications and changes in the construction and arrangement of the parts forming the invention may obviously be made and are contemplated, as the drawing and description are only 20 intended to illustrate a preferred embodiment thereof, and the right is therefore reserved to make such modifications as fall within the spirit and scope of the invention as hereinafter defined by the appended claims.

25 4. I claim as my invention:

1. A device of the class described comprising a member including two hook elements, the shanks of said hook elements being adapted to be pivotally connected to the rung of a ladder section, 30 a bar portion connecting said shank portions adjacent their hooked ends, a hook element formed integral with said bar and having an upwardly extending portion terminating in a bill provided with an eyelet and a downwardly extending portion, and spring means mounted on said ladder rung and engaging said downwardly extending portion to urge said hook elements forwardly and downwardly, the bills of said hook elements being adapted to normally engage rungs of a second ladder section to retain said first mentioned section in an elevated position.

2. A device as in claim 1, comprising means connected to said eyelet for raising and lowering said first mentioned ladder section, said means being operable to lift said member to raise the 45 bills of said hook elements upwardly and backwardly and out of engagement with the rungs of said last mentioned section for moving said sections relatively to each other, said spring means projecting said bills when said last mentioned means is released.

3. An operating mechanism for extension ladders comprising a connecting member adapted to be loosely mounted on a rung of a ladder section, said member including a plurality of integrally formed hooks having spaced bills adapted to move as a unit to selectively engage rungs of another ladder section, the bill of one of said hooks being provided with an eyelet, means connected to said eyelet for raising and lowering said first mentioned ladder section and for retaining said hooks in a retracted position out of engagement with said last mentioned rungs, said last mentioned hook having a depending shank extending toward the first mentioned rung, and spring means connected to said first mentioned rung and engaging said depending shank for protecting said hooks when said means is released.

4. An attachment for use with extension ladders, said attachment comprising a plurality of integrally formed hooks, certain of said hooks 20 having depending portions adapted to loosely engage a rung of a ladder section, means carried by said rung and engaging the shank of another of said hooks for projecting said hooks as a unit, the bills of said hooks being adapted to selectively engage rungs of a second ladder section when in a projected position, and means connected to one of said hooks for retracting the hooks as a unit and for raising and lowering said first mentioned ladder section.

5. A latch member for extension ladders comprising spaced hook elements having shanks adapted to pivotally engage a rung of a ladder section, a cross bar having its ends formed integral with the intermediate portions of said shanks, a hook element formed integral with the intermediate portion of said bar and disposed transversely thereto, said hook elements each having their upper ends bent to form hooks adapted to selectively engage a rung of a second ladder section, and a spring carried by said first mentioned rung for engagement with the opposite end of said last mentioned hook element to project the latch.

6. A device as in claim 5, comprising a cable 45 carried by said ladder sections, one end of said cable being connected to a portion of the hooked end of said last mentioned hook element for raising and lowering said first mentioned ladder section and for retracting said latch.

50 STANLEY E. DUNN.
